JEWELRY PENDANT OR SIMILAR ARTICLE

Samuel Stonberg, Merion, Pa., assignor to Opalite, Inc.,
Philadelphia, Pa., a corporation of Pennsylvania

Filed Nov. 7, 1960, Ser. No. 62,749

Term of patent 14 years

(Cl. D45—16)

The figure is an elevational view of a jewelry pendant or similar article showing my new design wherein the essential features are shown in full lines, and the sides not shown are substantially identical to the side shown, the whole being symmetrical about its vertical axis.

I claim:

The ornamental design for a jewelry pendant or similar article, substantially as shown and described.
